UNITED STATES PATENT OFFICE.

HENRY F. SAWTELLE, OF LEOMINSTER, MASSACHUSETTS.

HYDRAULIC MOTOR.

SPECIFICATION forming part of Letters Patent No. 728,987, dated May 26, 1903.

Application filed June 21, 1902. Serial No. 112,613. (No model.)

To all whom it may concern:

Be it known that I, HENRY F. SAWTELLE, of Leominster, in the county of Worcester and State of Massachusetts, have invented certain new and useful Improvements in Hydraulic Motors, of which the following, taken in connection with the accompanying drawings, is a specification.

My invention relates to hydraulic motors; and it consists in certain novel features of construction, arrangement, and combination of parts, which will be readily understood by reference to the description of the accompanying drawings and to the claims hereto appended and in which my invention is clearly pointed out.

Figure 1 of the drawings is a plan of a machine embodying my invention. Fig. 2 is an elevation of the same looking in the direction indicated by the arrow *a* on Fig. 1. Fig. 3 is an elevation looking in the direction indicated by the arrow *b* on Figs. 1 and 2. Fig. 4 is a partial elevation looking in the direction indicated by the arrow *c* on Figs. 1 and 3. Fig. 5 is a sectional plan of the main frame, the cutting plane being on line A A on Fig. 4. Fig. 6 is a sectional plan of the same frame, the cutting plane being on line B B on Fig. 3. Fig. 7 is a longitudinal section of the grip-operated sleeve and the driving bevel gear-wheel. Fig. 8 is a transverse section of the same on line C C. Fig. 9 is an elevation of one of the grip-levers. Fig. 10 is a section on line D D on Fig. 9. Fig. 11 is a front elevation of the valve-casing and its supporting stand with valves removed. Fig. 12 is a sectional side elevation of the same with caps and valves shown in section on line G G on Fig. 11. Figs. 13 and 14 are sections on lines E E and F F, respectively, on Fig. 12; and Figs. 15, 16, 17, 18, and 19 are details of the valve-casing caps, drawn to enlarged scale. Fig. 20 is a partial plan illustrating a modification of the arrangement of the shaft to be driven relative to the operating mechanism. Figs. 11, 12, 13, and 14 are also drawn to an enlarged scale.

In the drawings, 1 represents a bed-plate, upon which are erected the several parts of the machine. 2 is the main frame or stand, having formed in one piece therewith or secured thereto the two jack-cylinders 3 and 4 and is

provided at its upper end with the bearing 5, in which is mounted, so as to be revoluble therein, the sleeve 6, which has formed upon 55 or firmly secured to one end thereof the bevel gear-wheel 7 and the series of clutch-teeth 8, as shown in Figs. 1 and 2.

The sleeve 6 has mounted therein one end of the shaft 9 to be driven, which has other 60 suitable bearings, one of which is shown at 10, said shaft having loosely mounted thereon, so as to be freely revoluble about its axis in either direction, the bevel gear-wheel 11, the hub of which is also provided with a series of 65 clutch-teeth 12, the shoulders of which face in opposite directions to those on the gear-wheel 7. The gears 7 and 11 are connected by the intermediate gear-wheel 13, mounted upon a fixed stud set in the stand 14, as shown 70 in Fig. 1.

The shaft 9 has mounted thereon between the gears 7 and 11 the clutch-sleeve 15, provided at each end with clutch-teeth to alternately engage the clutch-teeth on the said 75 gears 7 and 11, said clutch-sleeve 15 being connected to the shaft 9 by a spline and groove in a well-known manner, so that it may be moved endwise on said shaft, but must revolve therewith.

The clutch-sleeve 15 is provided with a circumferential groove 16, with which the forked end of the shipper-lever 17 engages as a means of moving it endwise on said shaft whenever it may be desired to reverse the 85 motion of said shaft 9.

The jack-cylinders 3 and 4 have mounted therein the pistons 18 and 19, respectively, the upper ends of which are connected by suitable links with the free or movable ends 90 of the friction grip-levers 20 and 21, respectively, the hub end of which has formed therein a chamber, in the inner surface of which is formed an eccentric surface 22, joining a radial surface 23, whereby a curved 95 wedge-like pocket 24 is formed, in which is placed a hardened-steel roll 25, resting upon the periphery of the sleeve 6 and operating substantially as in said Patent No. 660,131, before referred to.

The pistons 18 and 19 have firmly secured to their upper ends and pendent therefrom the toothed racks 26 and 27, respectively, said racks being fitted to and movable end-

wise in vertical grooves 28 and 29, respectively, formed in the outer surfaces of the cylinders 3 and 4, the teeth of said racks engaging the teeth of the spur gear-wheel 30 upon opposite sides thereof, all as shown in Figs. 1, 4, 5, and 6.

The gear-wheel 30 is firmly secured upon one end of the horizontal shaft 31, mounted in bearings in the frame 2 and having secured upon its other end the bevel-pinion 32, the teeth of which engage the teeth of the bevel-gear 33, firmly secured upon the shaft 34, mounted in suitable fixed bearings and carrying the two-armed lever 35, the end of each arm of which is provided with a laterally-projecting stud 36, as shown in Figs. 1, 2, and 3.

As shown in the drawings, the shaft 34 has its bearings in the stands 37 and 38, secured to and projecting from the main frame or stand 2, as shown. The stand 38 has formed in one piece therewith or secured thereto the valve-casing 39, provided with two tapered perforations 40 and 41, (see Figs. 11 and 12,) in which are fitted the two plug-valves 42 and 43, respectively, said plugs being connected together by the spur-gears 44 and 45, as shown in Figs. 1, 2, and 3.

The valve-casing 39 is provided with four ports 46, 47, 48, and 49, extending transversely through the same in pairs, one pair, 46 and 47, being arranged in a horizontal plane cutting longitudinally through the axis of the tapering perforation 40, and the other pair, 48 and 49, being in like manner arranged in the plane of the axis of the tapered perforation 41, as shown in Figs. 11 and 12.

The valve-casing 39 has secured to its front side the cap 50, having formed in its inner face two chambers 51 and 52, separated by a horizontal partition 53, so arranged that the chamber 51 incloses and communicates with one end of each of the ports 46 and 47, and the chamber 52 incloses and communicates with one end of each of the ports 48 and 49. (See Figs. 12, 13, and 14.) In like manner the valve-casing has secured to its rear face the cap 54, in the inner face of which is formed two chambers 55 and 56, separated by a vertical partition 57. (See Figs. 12, 15, 16, and 17.)

The valve 42 has firmly secured thereto the two-armed lever 58, the end of each arm of which is provided with a laterally-projecting stud or lug 59, as shown in Figs. 1, 2, and 3.

Each of the valves 42 and 43 is provided with two lateral perforations 60 and 61 or 62 and 63, the two perforations in each valve being arranged at such an angle to each other that when one of said perforations is in line with one of the ports of the casing 39 that bisects the axis of said valve the other of said perforations will be out of alignment with the other of said ports, and in order to reverse the motions of the pistons 18 and 19 an alternating oscillating motion is imparted to said valves just sufficient to close the open passages through said valves and open those pre-

viously closed. This is accomplished by means of the two-armed lever 58 and the weighted lever 64, which is pivoted to the upper end of the valve-casing 39 and normally resting upon one or the other laterally-projecting stud 59 in a slightly-inclined position with its free end the lowest, as shown in Fig. 3, said lever being provided with the adjustable weight 65, mounted thereon in any well-known manner.

Each of the valve-casing caps 50 and 54 is provided with a projecting arm 66, which serve to limit the vibration of the two-armed lever 58 in either direction.

The laterally-projecting studs at the ends of the arms of the levers 35 and 58 extend across the plane of movement of the lever 64, as shown in Figs. 1 and 2.

The stand 10, in which the shaft 9 has one of its bearings, is provided with an arm 67, upon which the shipper-lever 17 is pivoted, and a curved or segmental arm 68 is secured to said stand and has formed in its upper edge two shallow notches 69 to receive the handle-arm of said shipper-lever to lock it at either extreme of its movement.

A double-acting pump 70, constructed and operating substantially as described in said prior patent, supplies a suitable liquid to the jack-cylinders 3 and 4 to alternately raise the pistons 18 and 19, and thus cause intermittent vibrations of the friction grip-levers 20 and 21 and corresponding movements of the sleeve 6 about its axis. A pipe 71 communicates at one end with the interior of the delivery-chamber of said pump at its base and at its other end with the interior of the chamber 51 in the cap 50, and a pipe 72 communicates at one end with the interior of the reservoir or liquid-supply chamber of said pump near its top and at its other end with the interior of the chamber 52 of the cap 50. A pipe 73 communicates at one end with the interior of the chamber 55 in the cap 54 and at its other end with the interior of the jack-cylinder 3 beneath its piston 18, and a similar pipe 74 communicates at one end with the chamber 56 in the cap 54 and at its other with the interior of the jack-cylinder 4 beneath its piston 19, as shown.

The pump 70 is shown as arranged to be operated by hand; but it may be operated in any other well-known manner.

The operation of my invention is as follows: The several parts of the machine being in the positions shown in the drawings—that is, with the piston 18 raised to the extreme of its upward movement and the piston 19 depressed to the extreme of its downward movement and the valves 42 and 43 being set as shown in Figs. 12, 13, and 14, so that communication is open between the chambers 51 and 55 through the valve 42 and between the chambers 52 and 55 through the valve 43—if the pump be operated with the reservoir properly charged the liquid will be forced through the pipe 71, the chamber 51, through the ports

46, through passage 60 of the valve 42 into the chamber 56, and thence through the pipe 74 to the interior of the cylinder 4 beneath its piston 19, and forces said piston and its rack 27 upward, thereby moving the end of the grip-lever 21 upward and causing it to grip the sleeve 6 and impart to it a movement about its axis to a limited extent, which motion is imparted through the gear-wheels 7, 11, and 13 and the clutch-sleeve 15 to the shaft 9 to partially rotate it in a direction opposite to the motion of the sleeve 6. The upward movement of the rack 27 causes a partial rotation of the gear-wheel 30, its shaft 31, and the bevel-pinion 32. The gear-wheel 30 by its engagement with the rack 26 when rotated by the upward movement of the piston 19 moves the piston 18 downward, thereby forcing the liquid contained in the cylinder 3 through the pipe 73, the chamber 55, the ports 49, the passage 63, through the valve 43, the chamber 52, and the pipe 72 into the reservoir of the pump 70. As the piston 19 and rack 27 move upward and the gear 30, with its shaft and the pinion 32, is rotated the bevel gear-wheel 33 and the two-armed lever 35 are moved about the axis of the shaft 34. The inner arm of the lever 35 acts upon the lever 64 to move its free and weighted end upward and outward about its pivotal connection until it has moved sufficiently past a perpendicular position for the force of gravity acting thereon to cause it to fall outward and downward, in which downward movement said lever strikes the lateral stud on the outer arm of the lever 58 with sufficient force to depress it into contact with a stop 66 and moves the valves 42 and 43 about their axes of motion to close the passages 60 and 63 through said valves and open the passages 61 and 62 through said valves 42 and 43, respectively, which instantly changes the current of moving liquid set in motion by the operation of the pump, the liquid discharged by said pump being forced 40 through the pipe 71 to the chamber 51 through the port 47, valve-passage 61, and pipe 73 to the interior of the cylinder 3 beneath its piston 18 to force said piston and its rack 26 upward, thereby causing the friction grip-lever 20 to engage the sleeve 6 and continue its motion in the same direction as before, while the motions of the gear-wheel 30, its shaft, the bevel-pinion 32, the gear-wheel 33, and the two-armed lever 35 are reversed and the lever 64, with its weight 65, is moved upward and inward by the action thereon of the outer arm of the lever 35, the piston 19 at the same time being moved downward by the action of the gear 30 upon the rack 27, thereby forcing 50 the liquid in the cylinder 4 through the pipe 74, the chamber 56, the casing-port 48, the valve-passage 62, the chamber 52, and the pipe 72 to the interior of the pump-reservoir. When the piston 19 has completed its downward stroke, the lever 64 will have been moved inward sufficiently beyond a perpendicular position for the action of gravity to cause

said lever to fall backward and inward and strike upon the lateral stud of the inner arm of the lever 58, when the valves are again reversed and the operations are repeated indefinitely. When it is desired to reverse the rotation of the shaft 9, the shipper-lever 17 is moved from the position shown in Fig. 1 of the drawings into a position in engagement with the notch 69, thereby causing the clutch-sleeve to be engaged by the clutch-teeth 8, connected to the bevel gear-wheel 7, when the shaft 9 will be revolved in the same direction as the sleeve 6.

In Fig. 20 a modification of my invention so far as relates to the relative arrangement of the driving mechanism and the driven shaft is shown, in which the sleeve 6 is omitted, and the grip-levers act directly upon the shaft 9, upon which the bevel gear-wheels 7 and 11 are loosely mounted, so as to be freely revoluble in either direction thereon, and the gear 13 is firmly secured upon the shaft 75 to be driven.

I claim—

1. In a hydraulic motor, the combination with the shaft to be revolved, of a sleeve mounted loosely on said shaft, a bevel gear-wheel and a series of clutch-teeth carried by said sleeve; a second bevel gear-wheel mounted loosely on said shaft; an intermediate bevel gear-wheel engaging both of said before-mentioned gear-wheels; a plurality of friction grip-levers mounted loosely on said sleeve and constructed and adapted to automatically couple said levers to said sleeve when moving in one direction, and to uncouple the same when moving in the other direction; a plurality of hydraulic jack mechanisms arranged in fixed positions at one side of said sleeve and shaft; means connecting the pistons of said jack mechanisms; a clutch-sleeve fitted to said shaft between the gears on said shaft and sleeve and movable endwise of and revoluble with said shaft; means for moving said clutch-sleeve endwise on said shaft to cause it to couple either one or the other of said gears to said shaft according to the direction that it is desired to revolve said shaft; and means for forcing liquid into the cylinders of said jack mechanisms beneath their pistons.

2. In a hydraulic motor, the combination with a shaft to be rotated, of a pair of jack-cylinders arranged in fixed positions at one side of said shaft; a pair of levers mounted loosely on said shaft and projecting over said cylinders; means for causing said levers to be automatically coupled to said shaft when moving in one direction about the axis of said shaft, and uncoupled therefrom when moving in the opposite direction; a piston mounted in each of said cylinders; a suitable connection between the outer end of each piston and the free or movable end of one of said levers; a toothed rack firmly attached to the outer end of each piston and depending therefrom outside of the wall of its cylinder, said racks

being arranged with their toothed sides facing each other; a spur gear-wheel located between said racks and engaging the teeth thereof upon opposite sides of its periphery so that 5 the outward movement of one piston will cause an inward movement of the other piston; means for forcing a liquid, alternately, into each of said cylinders beneath its piston, to force it upward; a valve mechanism for controlling the flow of said liquid; and means, comprising a weighted lever operated by gravity, for instantaneously reversing said valve mechanism.

3. In a hydraulic motor, the combination 15 with the mechanism to be operated thereby, of a plurality of hydraulic jack mechanisms arranged in fixed and parallel positions, and to act alternately; a pendent rack attached to the upper end of each piston of said jack 20 mechanisms; a gear-wheel arranged between said racks and engaged on opposite sides by said racks to compel the pistons of a pair to move in opposite directions; a double-acting pump; pipes leading from said pump to the 25 interiors of said cylinders beneath their pistons; a pair of oscillating valves constructed and arranged, the one to control the flow of the liquid from said pump to said cylinders and the other to control the return of the liquid 30 from said cylinders to said pump; a pair of spur gear-wheels connecting said valves to cause them to rotate in unison; and means, comprising a weighted lever, for automatically, and instantaneously reversing said 35 valves, and consequently the flow of the liquid.

4. In a hydraulic motor, the combination with the shaft to be revolved, of a pair of friction grip-levers constructed and arranged to alternately act upon said shaft to impart thereto a step-by-step rotation; a pair of hydraulic jack-cylinders arranged in fixed positions at one side of said shaft; a piston fitted and movable endwise in each of said cylinders; a toothed rack attached to and pendent from the upper end of each of said pistons; 45 the gear-wheel 30 mounted on one end of the shaft 31 and engaging both of said racks as set forth; the bevel-pinion 32 on the other end of said shaft 31; the valve-casing 39 provided with ports 46, 47, 48 and 49; the valves 42 and 43 provided respectively with the transverse passages 60 and 61, and 62 and 63, the passages in each valve being arranged at a different angle to a longitudinal plane as shown; the spur-gears 44 and 45 carried by said valves; the two- 50 armed lever 58, secured to the valve 42; the weighted lever 64; the bevel gear-wheel 33 mounted upon any suitable bearing and engaged by the pinion 32; and the two-armed lever 35 all constructed arranged and operating substantially as described.

In testimony whereof I have signed my name to this specification, in the presence of two subscribing witnesses, on this 19th day of June, A. D. 1902.

HENRY F. SAWTELLE.
